UNITED STATES PATENT OFFICE.

JOHN SZTOGRYN, OF NEWARK, NEW JERSEY.

LAUNDRY BOILER ATTACHMENT.

Application filed February 23, 1928. Serial No. 256,203.

The present invention relates to laundry boiler attachments and particularly for boilers embodying a plurality of compartments for boiling clothes of several persons.

5 In large laundry establishments one boiler is used having a number of compartments wherein laundries of individual customers are washed or boiled. It is the practice that the customers deliver their laundry to laundry 10 establishments in bags. Therefore, the principal object of the present invention is the provision of an attachment for a boiler such as hereinabove indicated upon which individual laundry bags may be suspended and 15 thus their loss or misplacement prevented.

Another object of the present invention is the provision of a hook associated with a door of a laundry boiler compartment, which remains in closed position when the compartment door remains closed, and which 20 automatically opens on opening the door.

With the above general objects in view and others that will appear as the nature of the invention is better understood, the same 25 consists in the novel construction, combination and arrangement of parts hereinafter more fully described, illustrated in the accompanying drawing and pointed out in the appended claims.

30 In the drawing forming a part of this application, and in which like designating characters refer to corresponding parts throughout the several views,

Fig. 1 is a top elevational view, partly in 35 section, of a laundry boiler with a plurality of compartments, with each of which the present invention is intended to operate;

Fig. 2 is a cross-sectional view along line 2—2 of Fig. 1, illustrating the position of 40 the invention when the door of one compartment with which the attachment cooperates, is closed;

Fig. 3 is a similar view illustrating the 45 position of the attachment with the compartment door open; and

Fig. 4 is a perspective view of a device within which the attachment is pivoted.

Fig. 5 is a sectional detail view of the tube, 50 rod, spring and socket used in my device.

Referring to the drawing in detail there is 55 shown a boiler of cylindrical formation generally indicated by 10 divided into a number of sections or compartments 11 by radial walls or partitions 12. The boiler further includes a stationary top wall or cover 13 which is positioned centrally of the boiler,

and which is of polygonal formation. Said cover is mounted upon the inner ends of said partitions 12. A number of doors 14 are affixed to the sides of said stationary cover 60 13 by means of hinges 15, each of said doors 14 overhanging one partition 11.

The above described construction of a laundry boiler is the usual construction. My invention includes a number of hooks 16, 65 each intended to operate with one partition 11, and particularly with door 14. Said hook 16 is positioned with the lower hook end below door 14, and has its inner end flattened as at 17, which is pivotally mounted upon 70 pin 18 and which is positioned within slot 19 in the casing 20, said slot 19 extending through said casing 20 at both of its ends, permitting therewithin free pivotal movement of the inner end of hook 16. Said 75 casing 20 is positioned within slot 21 of the door 14 and is mounted upon the door by means of screws passing through apertures 22 made in horizontal plates 23 integrally formed with and extending from the upper 80 end of said casing 20. Said inner flattened end 17 of hook 16 extends above door 14 and above plates 23 and is pivotally mounted upon pin 24 within bifurcated extension 85 of tube 26. Said tube 26 at its other end has an inward flange 27 for the purpose hereinafter stated.

The outer end of rod 28 is provided with head 29 which is receivable within said tube 26, and encompassing said outer end of said 90 rod 28 and interposed between said inner flange 27 and head 29 is a coil spring 30, which, normally, when door 14 is closed, remains compressed as seen on Fig. 2. The other end of said rod 28 is threaded and is 95 receivable within threaded socket portion 31 of the pivoted anchor 32. The length of said rod 28 may be adjusted by driving it within socket portion 31 or by extending the same therefrom. A nut 33 holds said rod 28 in its 100 adjusted position. The other end of said socket portion 32 is bifurcated as at 34 to receive therewithin lug 35 upon which said socket 32 is pivoted by means of pin 36, and upon which said socket 32 including rod 28 105 is adapted for angular shifting movement in a vertical plane. Said lug 35 is integrally formed with a horizontal plate 37 which is mounted upon the stationary section cover 13 and which is affixed thereto by means of 110 bolts 38 and nuts 39.

When door 14 is closed the outer end of

hook 16 remains within a thimble or paper, 40, as shown on Fig. 2. Further shifting movement of the outer end of hook 16 will be prevented by the bottom 41 of said thimble 40 and said thimble will be maintained in its position and guarded against displacement from door 14 by means of flange 42.

In the closed position of door 14, shown on Fig. 2, spring 30 remains compressed within tube 26, said spring exerting pressure at the head 29 of rod 28 and at the inner flange 27. By virtue of said pressure of spring 30 upon the inner flange 27 and also by virtue of the inherent horizontal position of said tube 26, rod 28 and socket member 32, the inner flattened end 17 of hook 16 above its pivot point 18 will be drawn toward the center of the laundry boiler, in consequence of which the outer end of said hook 16 will be maintained within thimble 40.

On opening door 14, the tube 26, rod 28, and socket member 32 take the position shown in Figure 3; that is they swing upwardly, in which case spring 30 will be expanded and the head 29 of the rod 28 will shift toward the outer end of the tube 26, but nevertheless will exert continuing pressure upon the inner flange 27. Tube 26 in that last described position will have a tendency 30 to push the inner end of hook 16 in the opposite direction from that last mentioned, which will cause the disengagement of the outer end of hook 16 from door 14 and thimble 40, bringing about the opening of said hook 16 as shown on Fig. 3.

From the hereinabove description it will be apparent that upon opening door 14 a laundry bag may be suspended upon hook 16. Thereupon on closing door 14 and 40 bringing hook 16 into the engagement with said door the suspended bag will remain locked upon hook 16 preventing any possibility of its disengagement until door 14 is again opened.

While there is described herein a preferred embodiment of the present invention, it is nevertheless to be understood that minor changes may be made therein without departing from the spirit and scope of the invention as claimed.

What I claim as new is:

1. In combination, a laundry boiler having a swinging door and a support to which it is hinged, a laundry supporting hook having one end pivoted to said door and the other end normally closely adjacent the inside of said door in its closed position, and a connection between the pivoted end of said hook and said support providing means to open and close said hook when said door is opened and closed respectively.

2. In combination, a laundry boiler having a swinging door and a support carrying the

door, a laundry supporting member mounted for swinging movement on said door and 65 normally held in a position closely adjacent said door for preventing removal of laundry therefrom, and a connection between the pivoted end of said member and said support providing means to swing said member to open and close said hook when said door is opened and closed respectively.

3. In combination, a laundry boiler having a door and a support carrying the door, a laundry supporting hook mounted for 75 swinging movement on said door, a keeper seated in an opening formed in the door for receiving an end of said hook when the hook is in closed position, and a connection between the other end of said hook and said support providing means for swinging the end of said hook into and out of the keeper carried by the door when said door is opened and closed respectively.

4. In combination, a laundry boiler having a swinging door and a support to which it is hinged, a U-shaped laundry supporting hook having one end extending through and pivoted to said door and the other end normally closely adjacent the inside of said door, a keeper carried by the door for receiving the end of the hook lying closely adjacent thereto, and a connection between the pivoted end of said hook and said support providing means to open and close said hook when said door is opened and closed, respectively.

5. The combination with a laundry boiler having a pivoted door, a hook inside said door having a shank on one end extending through said door, a tube pivoted at one end to the end of said shank and having an inner flange at its outer end, a socket pivotally connected with the boiler, a rod adjustably connected with said socket at one end and having a head at the other end mounted in said tube, a coil spring on said rod between said head and flange, said hook extending in the opposite direction from said tube and positioned with its free end adjacent the door when the latter is closed.

6. The combination with a laundry boiler having a pivoted door, a hook inside said door having a shank on one end extending through said door and pivotally connected with the door, a connection between the shank of the hook and the boiler providing means to swing the hook to open and closed position when said door is opened and closed respectively, and said connection formed with interfitting, relatively slidably portions, and a spring between said portions, to normally urge the hook toward the door.

In testimony wherof I affix my signature.

JOHN SZTOGRYN.
